CATHODE RAY TUBE

Nyman Levin, Finchley, London, England, assignor to Radio Corporation of America, a corporation of Delaware

Application February 2, 1937, Serial No. 123,564
In Great Britain February 3, 1936

5 Claims. (Cl. 250—162)

This invention relates to cathode ray tubes and has for its object to provide improved cathode ray tubes suitable for use in television systems and for similar oscillograph purposes where modulation of the intensity of a scanning cathode ray beam is required.

In present day cathode ray television reproducer tubes it is usual practice to focus a reduced image of the cathode on the fluorescent screen in the tube but a defect of this practice is that modulation of the intensity of the cathode ray produces alteration in the size of the spot on the screen and in general a "halo" is introduced round the image when the control electrode of the electron gun is at zero or negative potential. It has been proposed to cause the first anode of the electron gun to form the aperture whose image is focused on the screen, but known proposals of this nature present the disadvantage of increasing the number of electrodes necessary since the first anode does not take part in the actual focusing.

In accordance with one feature of this invention, the control electrode of the electron gun of a cathode ray tube is placed very close to a cathode whose dimensions are large relative to the size of the aperture in the said control electrode and focusing is then accomplished upon the said aperture by a succeeding electrode assembly constituting an electron lens assembly and so arranged as to be substantially unaffected by varying voltages applied to the control electrode. This involves that the first anode must be at a relatively large distance from the control electrode (as compared to the control electrode-cathode spacing) and must have a relatively much higher potential. For example, if the distance between the control electrode and the cathode is ".005\"", then the distance between the first anode and the control electrode should be about ".030\"", and the potential of the said first anode should be of the order of 2,000 volts. The electrode assembly succeeding the first anode may be designed to give either an electron accelerating or an electron decelerating region as may be required. The spot obtained on the screen will be a small image of the aperture in the control electrode and the arrangement may be so operated that this image will change substantially only in intensity and not in size or shape when the potential on the control electrode is changed by voltage modulated signals. Alternatively the arrangement may be so operated that the spot on the screen, although changing in size, never increases beyond a dimension determined by the size of the

picture and the number of scanning lines. For example, if the spot on the screen is to be 0.02" square, or if it is to be a circular spot of .02" diameter, the arrangement may be so operated that a spot of this size is obtained when the control electrode is at cathode potential. Accordingly when the control electrode becomes negative with respect to the cathode the spot will become smaller and of reduced intensity, but it can never become larger than the predetermined size.

The accompanying Figure 1 illustrates one form of construction in accordance with the invention. In Figure 1 a cathode ray tube comprises within an evacuated envelope E a cathode 1; an apertured control electrode 2 which is very close to said cathode and has an aperture considerably smaller than the cathode area; an accelerating anode 3 which is at a relatively large distance from the control electrode (as compared to the control electrode-cathode spacing) and has also a small aperture; a relatively long cylindrical electrode 4 having a small central aperture in each of its end faces; and a further apertured anode 5. These electrodes constitute the electron gun system and co-operate to project a ray of electrons towards a screen 6 which is mounted near the other end of the tube and may, if desired, constitute also a final anode. In practice, if the cathode 1 be taken as of zero potential, the control electrode 2 may be varied from —20 volts to zero, the accelerator anode 3 may be maintained at about 2,000 volts the cylindrical electrode 4 (hereinafter referred to for convenience of description as the second anode) may be maintained at zero potential, and the further anode 5 may be maintained at about 3,000 volts. The three anodes 3, 4, 5, may be arranged to produce an image of the aperture in the control electrode 2 on the screen 6 when the said control electrode is at about —10 volts, and if this be done a spot of substantially unvarying size will be obtained. Alternatively the three anodes 3, 4, 5 may be arranged to focus an image of the aperture of the control electrode on the screen when the control electrode potential is zero, and if this be done the spot, although varying in size, will never exceed a predetermined magnitude which it has for zero control electrode potential.

In accordance with another feature of the invention an "electronic field lens" is employed to obtain good definition of the spot in a cathode ray tube, and this lens is situated at a preliminary focus of a cathode or aperture which it is desired to focus on the screen. This feature of the invention enables satisfactory focusing to be

obtained and substantially avoids aberration and other forms of distortion without any need to introduce stops.

It will be appreciated that if focusing is obtained with a system including an electronic field lens situated at a preliminary focus of the cathode or aperture which it is desired to focus on the screen, and if the image is exactly in the plane of this lens, the size or focus of the image will not be affected. Any "halo" around the image must be diverging from a point outside the image plane and hence is caused to diverge from the field lens at so wide an angle as to be received by the plate or cylinder of the succeeding focusing lens. Thus the proportion of the "halo" passing through the aperture of the focusing lens will be so reduced as to be negligible.

The accompanying Figure 2 shows a construction embodying the last described feature of this invention. Here there is employed within an evacuated envelope a cathode 1 succeeded by a relatively closely spaced control electrode 2 whose aperture is smaller than the effective area of the cathode. The control electrode is in turn succeeded by three anodes 3, 4, 5, in succession, one (3) being an apertured plate, the second (4) being a relatively long cylindrical electrode having a central aperture in each of its end faces, and the third (5) being also an apertured plate. The tube further contains a screen 6 which, in this construction, is also an anode. Suppose it be desired to focus an image of the control electrode upon the screen. Then according to the potentials of the electrodes there will be formed preliminary focus F_1 in or near the aperture of that end plate of the cylindrical electrode 4 which is nearest the screen. Any "halo" will be caused by beam focusing at one side or other of the focus F_1 , and it will be appreciated that such rays as come to a focus at these longitudinally displaced points will, in passing through the cylindrical anode 4 (which provides the "field lens" action) be caused to become divergent through such a wide angle that they will be stopped by the anode 5, i. e., they will miss the aperture in the anode 5 altogether and will strike the metal of the said anode. In this way "halo" forming rays will be stopped but the correct desired beam which forms the spot image will not be affected. This action is illustrated in the explanatory dia-grammatic accompanying Figure 3, in which the chain lines represent "halo-forming" rays which pass through longitudinally displaced preliminary foci and will be stopped by the anode 5. In Figure 2 the chain lines also represent rays, but these rays are correctly focused rays which pass through the aperture in the anode 5.

The accompanying Figure 4 illustrates a third construction in accordance with this invention and embodying both features of the said invention. Here the tube comprises within an evacuated envelope a cathode 1, a control electrode 2 in the form of an apertured plate closely adjacent thereto, a first and second anode 3 and 3a each in the form of an apertured plate, a third anode 4 in the form of a cylindrical electrode having a central aperture in each of its end faces, and a fourth anode 5 in the form of an apertured plate in a cylinder 5a. All the apertures are, of course, in alignment from the cathode. The cylinder 5a may form part of a metal screening deposit provided on the interior wall of the envelope the screening being continued as shown at 5b into the usual flared part of the envelope. An example of practical electrode spacing for the

construction of Figure 4 is: distance between the control electrode 2 and the first anode 3 approximately .020"; distance between the first and second anodes 3, 3a about .020"; distance between the cathode 1 and the electrode 2—as small as possible practically; distance between the first aperture in the cylindrical electrode 4 (this aperture constitutes the field lens) and the anode 3a about 0.2". The first and second anodes 3, 3a form an image of the aperture of the control electrode 2 on the first aperture in the cylindrical electrode 4 and the second aperture in the said cylindrical electrode 4, in conjunction with the fourth anode 5, re-focus this image on the normally provided screen (not shown) at the end of the tube. For the practical case above cited the length of the cylindrical electrode 4 may be approximately 1" and the distance between the second aperture in this electrode and the aperture in the fourth anode 5 may also be about 1" and satisfactory results will be obtained with potentials of 1,000 volts, zero, 3,000 volts and 15,000 volts applied to the first, second, third and fourth anodes respectively. As regards aperture sizes the control electrodes 2 and the first anode 3 may, for the case cited, each have an aperture of .025" and the aperture in the second anode may be .035", the first and second apertures in the third anode being 0.50" and 0.2" in diameter respectively and the aperture in the fourth anode being 0.25" in diameter.

Having described my invention, what I claim is:

1. A cathode ray tube comprising, in the order stated, a cathode having a predetermined effective area of electron emission, an apertured disk control electrode closely adjacent thereto, the area of the aperture of said disk being smaller than the predetermined effective area of the cathode, two apertured disk anodes adjacent the control electrode, a cylindrical electrode having apertured end faces, and an apertured tubular electrode whose outside diameter is larger than the diameter of the cylindrical electrode, all of the apertures being in alignment along the axis of the cylindrical electrode and all of the apertured members being parallel to one another and lying in planes perpendicular to said axis.

2. A cathode ray tube comprising in the order stated a cathode having a predetermined effective area of electron emission, an apertured flat disk control electrode closely adjacent thereto, the area of the aperture of said disk being smaller than the predetermined effective area of the cathode, an apertured flat disk anode immediately adjacent the control electrode, a cylindrical electrode having apertured end faces, and a further apertured flat disk electrode, all of said apertures being aligned along a line passing through the axis of the cylindrical electrode and all of the flat disk electrodes and anode being parallel to one another and lying in planes perpendicular to said line.

3. A cathode ray tube comprising in the order stated a cathode having a predetermined effective area of electron emission, an apertured flat disk control electrode closely adjacent thereto, the area of the aperture of said disk being smaller than the predetermined effective area of the cathode, two apertured flat disk anodes immediately adjacent the control electrode, a cylindrical electrode having apertured end faces, and a further apertured flat disk electrode, all of said apertures being aligned along a line passing through the axis of the cylindrical electrode and all the flat disk electrodes and anodes being par-

allel to one another and lying in planes perpendicular to said line.

4. A cathode ray tube comprising in the order stated a cathode of relatively large emitting area, an apertured flat disk control electrode closely adjacent to and in register with the cathode, the area of the aperture of said control electrode being smaller than the emitting area of the cathode, a first apertured flat disk anode positioned in register with and at a relatively large distance from the cathode compared to the distance between the control electrode and the cathode, a tubular electrode having apertured end faces, and a second apertured anode, said tubular electrode and second anode being in register with said cathode.

5. A cathode ray tube comprising in the order stated a cathode having a predetermined effective area of electron emission, an apertured flat disk control electrode closely adjacent thereto, the area of the aperture of said disk being smaller than the predetermined effective area of the cathode, two apertured flat disk anodes immediately adjacent the control electrode, a cylindrical electrode having apertured end faces, and an apertured tubular electrode, all of said apertures being aligned along a line passing through the axis of the cylindrical electrode and all the flat disk electrodes and anodes being parallel to one another and lying in planes perpendicular to said line.
